UNITED STATES PATENT OFFICE.

NOAH F. TILLERY, OF OREGON, MISSOURI, ASSIGNOR OF ONE-HALF TO OTTIE WALL,
OF ST. JOSEPH, MISSOURI.

ELECTRIC LAMP-ADAPTER.

1,240,786.

Specification of Letters Patent. Patented Sept. 18, 1917.

Application filed April 12, 1917. Serial No. 161,636.

To all whom it may concern:

Be it known that I, NOAH F. TILLERY, a citizen of the United States of America, residing at Oregon, in the county of Holt and

5 State of Missouri, have invented certain new and useful Improvements in Electric Lamp-Adapters, of which the following is a specification.

The object of my invention is to provide 10 a means whereby an oil lamp may be converted into an electric lamp without dispensing with the oil lamp.

I accomplish my object by the mechanism illustrated in the accompanying drawings 15 and specifications in which,

Figure 1 is a side view of an oil lamp, partly broken away, to show the electric adapter;

Fig. 2 is a front view of an oil lamp with 20 the door open, also showing the electric adapter;

Fig. 3 is a front view of said oil lamp electric adapter;

Fig. 4 is a side view of Fig. 3, and 25 Fig. 5 is a top view of Fig. 3.

Similar letters refer to similar parts throughout the specifications, the letter A representing an ordinary automobile lamp.

B is a circular vertical clamp adapted to 30 hold an electric socket C. B' is a strip of metal bent centrally inward forming a small loop the two ends of said metal strip forming circular clamps or arms to engage electric socket C. D is a spring wire frame

35 which supports and holds in position said electric socket. E is an electric bulb having connection with said socket, and H H . . .

represent a plurality of electric wires. J J are duplicate hand holds to assist in placing 40 or removing the adapter from the lamp.

In this invention I do not limit myself to any particular style of wire, or composition, of material, as the wire or composition may be bent to form the results desired.

What I claim and desire to secure by Letters Patent, is:

1. In a device of the kind described, an electric socket holder consisting of a strap having a loop formed therein and arms curved outwardly from said loop to form a 50 socket receiving portion, a spring frame having a portion bent upwardly from its base to form a loop, said loop being widened at its upper portion to receive the loop of the socket holder, and being diminished at 55 its base, the spring frame having lateral portions bent circularly upward from its base, which portions are adapted to exert an outward pressure to hold the device in a lamp, said lateral portions having downwardly bent ends to form hand holds to assist in the replacement and removal of the device from a lamp.

2. In a device of the kind described the combination of a spring wire frame having 65 spring arms of general circular shape and a portion bent to form a loop and an electric socket holder received in said loop.

3. A device comprising a spring wire frame having spring arms a portion bent to 70 form a loop, an electric socket holder supported by said loop, and said frame having handholds to assist in the replacement and removal of an adapter from a lamp.

In testimony whereof I affix my signature 75 in the presence of two witnesses.

NOAH F. TILLERY.

Witnesses:

H. P. LEIGH,
E. F. HARTZELL.
